UNITED STATES PATENT OFFICE.

GEORGE R. AINSWORTH, OF GREAT NECK, NEW YORK.

DESIGN FOR AN ELECTRIC-LIGHT FIXTURE.

51,629.

Specification for Design.

Patented Jan. 1, 1918.

Application filed October 2, 1917. Serial No. 194,402. Term of patent 3½ years.

To all whom it may concern:

Be it known that I, GEORGE R. AINSWORTH, a citizen of the United States, and a resident of Great Neck, Nassau county, New York, have invented a new, original, and ornamental Design for Electric-Light Fixtures, of which the following is a specification, reference being had to the accompanying drawing, in which the figure shows a front elevation of a fixture embodying my invention.

The design comprised in this invention

consists essentially of a pendant electric light fixture, having an ornamental yoke in the form of a stirrup supporting horizontal platforms connected by intermediate bars; these in turn carry the lights. From the bottom of each globe extends a pendant ornament.

What I claim is:

The ornamental design for an electric light fixture as shown and described.

GEORGE R. AINSWORTH.
